ATTORNEY

UNITED STATES PATENT OFFICE

CHARLES L. MANGANO, OF GOUVERNEUR, NEW YORK

SHINGLE

Application filed April 30, 1930. Serial No. 448,690.

This invention relates to roof coverings and more particularly to shingles of the character which are fabricated from sheet material of a fibrous nature, treated with bituminous material to impart weather resistant qualities thereto, and to render them flexible and non-porous and the shingle and especially the locking means provided thereon forming the subject matter of my invention is an improvement over other shingles in that it permits not only one but several arrangements of the shingles with relation to each other and thus give the purchaser of the shingles his choice in the arrangement of the shingles while the manufacturer need only make practically one type of shingles together with suitable types of starter shingles and possibly different sizes of shingles.

Another object of the invention is to provide such a shingle with novel means for efficiently locking a plurality of them to one another and hold the butt of each shingle stiff and straight.

Another object of the invention is to provide a locking member for the shingles which will prevent the butt of the shingle from being lifted by wind or warping.

These and other objects of this invention will be apparent from the drawings, the specification and the appended claims forming a part thereof.

In the accompanying drawings:

Figure 1 is a detail perspective view of one of my improved shingles looking at the front or face thereof.

Figure 2 is a detail perspective view of one of my improved shingles looking at the rear or back thereof.

Figure 3 is a perspective view of three of the shingles in process of being locked together in one of the arrangements.

Figure 4 is a perspective view of my improved shingles in the process of being locked together in another arrangement.

Figure 5 is a detail perspective view of one of my improved shingles looking at it from the rear and illustrating how the locking strip is folded on the shingle which is locked to the starter shingle in the arrangement illustrated in Figure 4.

Figure 6 is a detail perspective view of one of the starter shingles looking at it from the rear.

Figure 7 is a plan view of a series of my shingles arranged and locked together for a single layer roof with the shingles in line with each other.

Figure 8 is a plan view of a series of my shingles arranged and locked together for a single layer roof with the shingles in staggered relation to each other.

Figure 9 is a plan view of a series of my shingles arranged and locked together for a triple layer roof in which three layers of shingles overlap each other.

Figure 10 is a plan view of a corner of a roof in which my shingles are arranged and locked together in angular relation to each other.

In the several figures of the drawings like reference numerals indicate like parts.

As illustrated in Figures 1 and 2 each individual shingle or unit indicated by reference numeral 3 consists of a rectangular section or sheet of water proof and weather proof fibrous material which may be either of uniform thickness or which may be heavier at one side as will hereinafter be described. At the bottom each of the shingles has a flange 4 bent upwardly at the back thereof to provide a flap at the back of each shingle. At the lower right hand end each shingle is cut away as indicated at 5 and the flap formed at the back of each shingle extends from the left hand side of the shingle to this cut away portion at the right hand side thereof. The corners of the flange 4 which forms the flap are angularly cut away at each end thereof.

Fastened into the fold of the flap of each of the shingles is the metal locking strip 6. This strip is riveted to the flange 4 as illustrated at 7 and 8 in Figure 2 and projects about an inch from the left hand side of the shingle near the lower corner thereof.

In Figure 3 I have illustrated how the separate shingles or units 3 are interlocked with one another as a course of them is laid in covering a roof. The shingles are properly lined up with each other and each of them is nailed to the roof with suitable nails which

are driven approximately as indicated in the dotted line positions marked 9 and 10 in Figure 3. The nail driven into the position indicated by reference numeral 9 is located so that the projecting end of the locking strip 6 of the succeeding shingle may be inserted in an angular position below this nail into the end of the narrow channel at the back of the shingle so that after the end of the locking strip has been engaged into the channel, the shingle with the locking strip may be brought in line with the shingle already fastened to the roof in such a manner that the overlapping lower end of the new shingle will engage into the cut away portion of the anchored shingle and thus bring the lower edge of the new shingle in perfect alignment with the anchored shingle. This is illustrated in Figure 3. Each shingle thus has its left hand end overlap the right hand end of the preceding shingle a distance equal to the length of the cut away portion provided at the lower right hand corner of each of the shingles while the locking strip 6 thereof engages the narrow channel of the preceding shingle which has been fastened to the roof and thus locks the lower corner of the left hand side to the preceding shingle. The right hand end of each shingle as well as the upper end thereof is then nailed to the roof in any suitable manner except that the nail driven into the position indicated by reference numeral 9 in Figure 3 must be located as pointed out above in order to permit the next shingle to be locked to the shingle in process of being fastened to the roof. The nails for fastening the right hand side and top of the shingle are of course located so that as other courses of shingles are laid, their lower edge will overlap and cover the heads of the nails so that they will not be exposed to the weather.

In Figures 7 to 10 inclusive I have illustrated some of the various arrangements in which the shingles may be laid to cover a roof. The arrangement illustrated in Figure 7 provides a single layer roof in which the sides of the shingles are in line with each other. The arrangement illustrated in Figure 8 illustrates a single thickness roof in which the shingles are staggered with relation to one another. Figure 9 illustrates a triple thickness roof in which three courses of shingles overlap one another. A double thickness (not shown) is similarly arranged. The arrangement illustrated in Figure 10 shows the shingles laid in angular courses. In this arrangement a starter shingle 12 is needed to start off each course at the edge of the roof with a straight instead of an angular bottom. This is illustrated in Figures 4 and 10. The starter shingle used for this purpose is illustrated in perspective in Figure 6 and has a flap formed by the flange 13 at the back thereof. The left hand end of this starter shingle is cut away at 14 similar to the cut

away portion 5 of the shingle 3 and the right hand end of the starter shingle is cut away as indicated at 15 to permit the first of the shingles 3, 3 to engage and overlap the starter shingle as illustrated in Figure 4. The projecting portion of the locking strip of the shingle which is placed against the starter shingle is bent back at right angles as shown in Figure 5 which illustrates a shingle prepared in this way looking at it from the rear. The bent up portion of this shingle can thus engage under the edge and side of the starter shingle and thus lock this shingle to the starter shingle. The remainder of the shingles are laid and locked together in the same way as described in connection with Figures 1 to 3 inclusive except that each course of shingles extends at an angle to the edge of the roof instead of being parallel thereto.

The fact that a flange is provided at the bottom which is bent back makes the bottom of the shingle thicker than the sides. For this reason one side or the top of each single may be made thicker along the edge in order to make it look as thick as the bottom or nearly so. This is especially desirable when the shingles are laid only in the angular arrangement as it will make both of the exposed edges appear the same in thickness and not one heavier than the other.

I claim:

1. A flexible shingle having a flange bent up at the back to form a rear flap along one edge thereof, a locking strip anchored in the fold of said flap and projecting from one end of said shingle, the other end of said shingle being cut away to permit the engagement of the flap of the succeeding shingle under a portion of the first named shingle with the bottom edges of both shingles in line with each other, said locking strip being adapted to engage into the fold of the flap of the preceding shingle to hold the shingle locked hereto.

2. A flexible shingle having a flange bent under to form a flap along one edge thereof, a fastening member comprising a narrow metal strip anchored in the fold of said flap and forming a continuation of said flap of reduced width and projecting from one end of said shingle to engage under a portion of the end of the preceding shingle with the fastening member of the succeeding shingle engaging into the fold of the flap of said preceding shingle.

3. A flexible shingle having one edge thereof cut away a predetermined distance at one end thereof, a flange bent under to form a flap in back of said shingle beginning at the cut away edge thereof, and a locking strip anchored in the fold of said flap and projecting from said shingle at the opposite end from the cut away portion.

In testimony whereof I affix my signature.

CHARLES L. MANGANO.
